DRY CLEANING APPARATUSES

John P. Jorgenson, Wilmette, Ill., assignor to Ayr-Mor Machinery Co., Inc., a corporation of Illinois

Application August 30, 1951, Serial No. 244,313

9 Claims. (Cl. 68—18)

This invention relates to improvements in dry cleaning apparatuses.

In the use of dry cleaning devices, after the washing and extracting cycles, heated air is usually circulated through the garments to remove any remaining cleaning fluid therefrom and to perform final drying and deodorization. In the conventional machine the air is blown transversely into the periphery of the cylinder in the upper portion thereof, and the outlet for the air is usually located in the upper portion opposite the intake. As a result, a good deal of the heated air bypasses the garments because the latter are being tumbled principally in the lower portion of the cylinder. Thus the drying cycle takes longer than is necessary and is not particularly efficient.

It is a general object of the present invention to provide dry cleaning apparatus which is constructed to provide for maximum recovery of the solvent remaining in the garments after extraction, by providing for maximum air recirculation through the garments in a very efficient manner.

A further object of the invention is to provide a device as above described wherein the deodorization of the garments takes place more rapidly.

A more specific object of the invention is to provide a dry cleaning device which includes a substantially closed suction system for causing circulation of air, with the inlet and outlet to the cylinder so arranged as to provide for maximum contact with the tumbling garments.

A further object of the invention is to provide a construction as above described wherein the air movement is in a downward direction to correspond with the natural tendency of the heavy cleaning vapors to descend.

A further object of the invention is to provide dry cleaning apparatus as above described which, because of the suction system and efficient arrangement of parts, makes it possible to use a relatively small condenser and heater and relatively small ducts and ports, there being highly efficient results notwithstanding such small size.

A still further object of the invention is to provide dry cleaning apparatus which is so constructed as to permit the use of a lower drying temperature thereby reducing shrinkage, eliminating the possibility of setting stains and the possibility of other damage caused by excessive temperatures.

A more specific object of the invention is to provide dry cleaning apparatus wherein there is a hollow perforated drive shaft through which heated air is introduced into the cylinder, there being an outlet in the lower portion of the device for withdrawing the air and vapors, and there being a diametrically extending perforated partition to eliminate the possibility of garments winding on the axial drive shaft.

A further object of the invention is to provide dry cleaning apparatus wherein the maximum recovery of cleaning fluid is made possible with resulting economy of operation.

With the above and other objects in view, the in-

2

vention consists of the improved dry cleaning apparatus and all of its parts and combinations, as set forth in the claims, and all equivalents thereof.

In the accompanying drawings illustrating one complete embodiment of the preferred form of the invention, in which the same reference numerals designate the same parts in all of the views:

Fig. 1 is a perspective view of the improved dry cleaning machine, parts being broken away;

Fig. 2 is a fragmentary perspective view of the cylinder and associated parts, portions being broken away to illustrate the interior, the view looking principally at the opposite end from that which is being viewed in Fig. 1;

Fig. 3 is an enlarged fragmentary vertical sectional view through one end of the cylinder and casing to show the hollow shaft arrangement and bearings therefor; and

Fig. 4 is a fragmentary perspective view showing the upper portion of the loading end of the casing.

Referring more particularly to the drawings the unit includes an outer generally cylindrical casing 10 supported on a suitable base 10', which base may serve as a housing for associated mechanism. Extending axially of the casing 10 is a shaft 11 (see Fig. 2). One end of the shaft projects from the end of the casing and has a pulley 12 rigidly mounted thereon. The pulley 12 is connected by an endless driving belt 13 with the pulley 14 on the shaft of an electric motor 15. The end of the shaft which has the pulley is suitably journaled in a bearing 16 at one end of the casing 10.

Within the casing 10 the drive shaft, throughout the major portion of its length, is hollow and provided with perforations 17 as is clear from Fig. 2. At the opposite end of the casing the end of the hollow portion of the shaft is open as at 18 (see Figs. 2 and 3) and said end

is suitably journaled in a bearing 19 carried by the end 20 of the casing, there being a cap 21 connected to the outer side of the bearing assembly by bolts 21'. The open end 18 of the drive shaft 11 projects into the hollow interior of the cap 21 and there is a circular seal 22 positioned around the shaft 11 and sealing the space between the exterior of the latter and the inner wall portion of the cap 21. Another seal 23 surrounds the exterior of the shaft 11 as illustrated in Fig. 3.

Connected to the shaft 11 for rotation therewith is a cylinder 24 having a loading opening 25 in one end wall 26, which opening is adapted to be closed by a suitable door 27. The opening 25 is adapted to be placed in registration with a similar opening in the wall 20 of the casing, which opening is normally closed by a door 55. The opposite end 28 of the cylinder 24 is closed and unperforated. The peripheral wall 29 of the cylinder is provided with perforations 30 substantially throughout its area.

A diametrically extending partition 31 having perforations 32 substantially throughout its area divides the cylinder into two semi-cylindrical chambers. The partition 31 is supported at its end edges between pairs of gusset plates 33, there being suitable bolts 34 extending through the plates and partition. The plates at each end

of the cylinder are connected to the exterior of a short sleeve 35, and each sleeve has its inner end formed with a flanged seat 36 for receiving the ends of a sleeve 37. The sleeve 37 is perforated as at 38 substantially throughout its length and said sleeve is of substantially larger diameter than the drive shaft 11, the latter extending through the sleeve as is clear from Figs. 2 and 3.

The apparatus illustrated in the drawing is designed to perform all of the necessary dry cleaning operations, there being a washing cycle, an extracting cycle, and a drying cycle. The present invention, however, relates to the last-mentioned cycle and therefore the apparatus which is employed in the other cycles has not been de-

scribed in detail. However, there is a dump valve 39 which may be electrically operated in a suitable manner and which controls the flow of cleaning fluid from the bottom chamber 40 (see Fig. 2) of the casing through an outlet duct 41 which leads to a port 42 in the dump valve assembly. Another port 43 in the dump valve assembly communicates with a line 44. When the dump valve is in the position shown in Fig. 1 vapors will recirculate through the line 44. When the valve is opened, however, liquid is permitted to flow through the discharge line 45, 10 which line may lead to a tank or reservoir.

Another line 46, which extends from the cylinder to the discharge pipe 45 is an overflow line for controlling the height of liquid within the washing cylinder during the washing operation. Cleaning fluid, preferably perchlor-ethylene is directed into an opening 56 in the top of the cylinder through a loading line 57.

When the drying cycle with which the present invention is concerned is being carried out, the valve in the valve assembly 39 is in the position shown in Fig. 1. The purpose of the drying cycle is to remove any remaining cleaning fluid from the garments which may be left in them after the extracting cycle. This not only results in a reclaimation of these remaining quantities of cleaning fluid, with resulting economies, but it also completes the drying 20 of the garments and the deodorization thereof.

At the time the drying cycle is being carried out there is, of course, no cleaning fluid in the cylinder or casing 10 except the small quantity which remains in the garments. During this cycle the discharge conduit 41 at the bottom of the casing serves as a suction opening through which vapors are removed. These vapors then pass through the pipe 44 and into a suitable condenser 47 where any solvent is removed by the condensation process and then returned to the solvent storage tank for further use. From the condenser 47 air passes through a line 48 leading to the center of a suction fan 49. The latter has an outlet opening 50 through which the air is discharged centrifugally into the line 51, the latter leading to a heater 52. In the line 51 is a vent or air outlet opening 53 and there is also an air valve assembly 54 leading from an air inlet opening 54'.

Air which has been heated in the heater 52 is circulated through the pipe 53 which leads into the opening of the hollow bearing cap 21. This heated air is then directed into the open end 18 of the hollow drive shaft 11 where it emerges from the perforations 17 of the shaft into the space between the shaft and sleeve 37 and then emerges from the perforations 38 in the sleeve 37.

During the drying cycle air is circulated and recirculated through the cylinder a predetermined number of times to remove all cleaning solvent from the garments. At the end of the drying cycle the air valve 54 automatically closes off communication between the pipe 51 and the heater 52 with the result that the air delivered by the suction fan is then exhausted to the outside atmosphere through the vent 53. While this is taking place the valve 54 has opened communication between the air inlet opening 54' and the pipe leading to the heater 52 to draw in fresh air from the atmosphere. This fresh air performs the final deodorization of the garments. This same arrangement is also useful during the period of loading garments into the cylinder. By turning on the fan any vapors which may remain in the cylinder are exhausted to the outside atmosphere through the vent 53 and are thus prevented from escaping into the room. While the solvent reclaiming process is in operation during the drying cycle then, of course, the valve 54 is in a position to shut off communication with the opening 54' and to permit flow from the pipe 51 into the heater. During this part of the cycle the vent 53 serves to relieve any undue pressures which might develop on the discharge side of the suction fan.

With the above structure it is apparent that as soon

as the suction fan 49 goes on, after an extracting cycle has been completed, that air and vapors will flow as indicated by the arrows in Fig. 2. Each time the vapors pass into the condenser additional cleaning fluid is removed, which fluid may be suitably returned to the storage tank. After the air leaves the condenser it is reheated by the heater 52 so that it is in a condition to pick up more solvent from the garments which are being tumbled in the rotating cylinder.

Due to the use of the hollow perforated shaft 11 and to the fact that there is a suction effect in the chamber 40 below the bottom of the cylinder, the heated air is continually pulled in a downward direction so that there is maximum contact of the heated air with the tumbling garments, which garments are usually tumbling in the lower portion of the cylinder. The generally downward movement of the heated air is highly efficient because when it becomes saturated with the perchlorethylene cleaning fluid, the latter is heavy and naturally wants to descend.

With the substantially closed suction arrangement illustrated there is a partial vacuum in the system so that lower drying temperatures may be employed because of the fact that the solvent will vaporize at a lower temperature when it is under a vacuum. Thus high drying temperatures are unnecessary and there is less danger of shrinkage, setting of stains, or other damage usually caused by excessive temperatures.

Various changes and modifications may be made without departing from the spirit of the invention and all of such changes are contemplated as may come within the scope of the claims.

What I claim as the invention is:

1. Dry cleaning apparatus comprising: a cylinder mounted for rotation on a substantially horizontal axis, a hollow perforated drive shaft extending axially through and fixed to said cylinder, said cylinder having a perforated periphery, a condenser, means including an exhaust conduit for receiving air from the cylinder which has left the latter through the perforated periphery thereof and for conducting the same to said condenser, a heater, a conduit between said condenser and heater, a suction fan in said conduit, said conduit having an air outlet opening between the fan and heater, a valve selectively controlling the flow either to the heater or through said air outlet from said fan, and means leading from said heater for conducting heated air into an end of said hollow shaft.

2. Dry cleaning apparatus comprising an outer casing having an end bearing, a drive shaft extending horizontally through said casing and having an end journaled through said bearing, a cylinder having a perforated periphery mounted on said shaft within said casing and rotatable with the shaft, portions of said drive shaft within the cylinder being hollow and perforated and said hollow portion extending adjacent said bearing, an exhaust duct for exhausting air from the cylinder through the perforated periphery thereof, conduit means connecting said exhaust duct with the hollow portion of said drive shaft adjacent said bearing to provide a normally closed circuit, and a suction fan in said conduit means normally maintaining a partial vacuum in the casing.

3. Dry cleaning apparatus comprising an outer casing having an end bearing, a drive shaft extending horizontally through said casing and having an end journaled through said bearing, a cylinder having a perforated periphery mounted on said shaft within said casing and rotatable with the shaft, portions of said drive shaft within the cylinder being hollow and perforated and said hollow portion extending adjacent said bearing, an exhaust duct for exhausting air from the cylinder through its perforated periphery, a condenser, normally closed conduit system, said system including a conduit connecting said exhaust duct with one end of said condenser to conduct exhausted air thereto, a heater, said system also includ-

ing a conduit connecting the heater with the other end of said condenser, a suction fan in said conduit system, and said conduit system including conduit means extending from said heater to the hollow portion of said drive shaft which is adjacent said bearing to complete said closed circuit, said suction fan normally maintaining a partial vacuum in the casing and cylinder.

4. Dry cleaning apparatus comprising an outer casing having an end bearing, a drive shaft extending horizontally through said casing and having an end journaled through said bearing, a cylinder having a perforated periphery mounted on said shaft within said casing and rotatable with the shaft, portions of said drive shaft within the cylinder being hollow and perforated and said hollow portion extending adjacent said bearing, an exhaust duct at the bottom of the casing for exhausting air from the cylinder through the bottom portion of its perforated periphery, a condenser, a conduit connecting said exhaust duct with one end of said condenser to conduct exhausted air thereto, a heater, a conduit connecting the heater with the other end of said condenser, a suction fan in said conduit, means including a valve in said conduit between said fan and heater constructed to selectively permit exhaust of air from the fan to the exterior, means for admitting outside air to the conduit system whenever air is being thus exhausted, and conduit means extending from said heater to the hollow portion of said drive shaft which is adjacent said bearing to provide a normally closed circuit, said suction fan normally maintaining a partial vacuum in the casing and cylinder.

5. A dry cleaning apparatus comprising: a cylinder rotatably mounted on a substantially horizontal axis; a hollow perforated drive shaft extending axially through said cylinder to which said cylinder is fixedly connected, said cylinder having a perforated periphery; a perforated sleeve fixed to and extending axially within the cylinder and radially spaced from and coaxial with and enclosing the hollow perforated drive shaft; a perforated diametric partition extending between said sleeve and the periphery of the cylinder dividing the cylinder into two semi-cylindrical sections; means for conducting heated air into the hollow drive shaft; and means including an exhaust duct for exhausting air from the cylinder through the perforated periphery thereof.

6. Dry cleaning apparatus comprising a cylinder having a perforated periphery; a hollow perforated drive shaft of relatively small diameter extending axially through said cylinder to which said cylinder is fixedly connected; means for rotatably supporting said drive shaft in a substantially horizontal position; a relatively short sleeve at each end of and within the cylinder surrounding the drive shaft; gusset plates projecting from said sleeves; a perforated sleeve surrounding the perforated drive shaft and of larger diameter than said drive shaft and extending between said first mentioned sleeves; perforated partition means extending between said sleeve and the periphery of the cylinder and dividing the cylinder into two semi-cylindrical sections, portions of said partition means being connected to said gusset plates, means for conducting heated air into the hollow drive shaft while the latter is rotating, and means for exhausting air from the cylinder through its perforated periphery.

7. Dry cleaning apparatus comprising a cylinder having a perforated periphery; a hollow perforated drive shaft of relatively small diameter extending axially through said cylinder to which said cylinder is fixedly connected; means for rotatably supporting said drive

shaft in a substantially horizontal position; a relatively short sleeve at each end of and within the cylinder surrounding the drive shaft, said sleeves having annular end seats which face one another; gusset plates projecting from said sleeves; a perforated sleeve surrounding the perforated drive shaft and of larger diameter than said drive shaft and having its ends supported in the annular end seats of the short sleeves; perforated partition means extending between said sleeve and the periphery of the cylinder and dividing the cylinder into two semi-cylindrical sections, portions of said partition means being connected to said gusset plates, means for conducting heated air into the hollow drive shaft while the latter is rotating, and means for exhausting air from the cylinder through its perforated periphery.

8. Dry cleaning apparatus comprising an outer casing having an end bearing, a drive shaft extending horizontally through said casing and having an end journaled through said bearing, a cylinder having a perforated periphery mounted on said shaft within said casing and rotatable with the shaft, portions of said drive shaft within the cylinder being hollow and perforated and said hollow portion extending adjacent said bearing, an exhaust duct for exhausting air from the cylinder through its perforated periphery, a condenser, a conduit system, said system including a conduit connecting said exhaust duct with one end of said condenser to conduct exhausted air thereto, a heater, said conduit system including a conduit connecting the heater with the other end of said condenser, a suction fan in said conduit system, means including a valve in said conduit between the heater and condenser constructed to selectively permit exhaust of air to the exterior, and means for admitting outside air to the conduit system whenever air is being thus exhausted, said conduit system including a conduit extending from said heater to the hollow portion of said drive shaft which is adjacent said bearing to provide a normally closed circuit, said suction fan normally maintaining a partial vacuum in the casing and cylinder.

9. Dry cleaning apparatus comprising: a cylinder mounted for rotation on a substantially horizontal axis, a hollow perforated drive shaft extending axially through and fixed to said cylinder, said cylinder having a perforated periphery, a condenser, a conduit system including an exhaust conduit for receiving air from the cylinder which has left the latter through the perforated periphery thereof and for conducting the same to said condenser, a heater, said conduit system including a conduit between said condenser and heater, a suction fan in said conduit system, said conduit system having an air outlet opening between the condenser and heater, a valve selectively controlling the flow either to the heater or through said air outlet, and said conduit system including means leading from said heater for conducting heated air into an end of said hollow shaft.
